UNITED STATES PATENT OFFICE.

LAWRENCE CRUNCLETON AND FRED L. CRUNCLETON, OF PHARR, TEXAS.

COMBINED GRATING AND SPRAY FOR REFRIGERATOR CARS.

Application filed June 29, 1926. Serial No. 119,485.

The present invention relates to a combined grating and water spraying for refrigerating cars.

The primary purpose of our improved contrivance is to melt the ice out of the bunkers of the common refrigerator cars now in use to reduce the tonnage in transit when returning the cars to their initial loading point.

Another very important object of the invention is the provision of a contrivance of this nature which will function as an efficient and reliable grating, thereby eliminating the necessity of the wooden grating now in common use.

Another very important object of the invention is to provide a contrivance of this nature which is exceedingly simple in its construction, compact and convenient, capable of being placed in practically all refrigerator cars now in common use with little or no alteration therein, a contrivance which is capable of being manufactured at a very low cost, and is otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is an elevation of the contrivance embodying the features of our invention, showing the same incorporated in a refrigerator car bunker, the latter being indicated in dotted lines, and

Fig. 2 is a perspective view of the main portion of the contrivance.

Referring to the drawing in detail, it will be seen that the numeral 5 designates a rectangular tubular frame, having a plurality of tubular cross members 6 attached thereto or formed integrally therewith. The frame 5 and the cross member 6 are provided with a plurality of spraying orifices 7 and 8 respectively which may be distributed as found necessary.

A pipe 9 rises from one corner of the frame 5 and is adapted to pierce a suitable opening provided in the roof of the car or in any other suitable point therein so that an extension 10 may be attached to a coupling 11 provided at the top of the pipe 9

for engaging the contrivance with a suitable source of water.

Referring particularly to the dotted line disclosure in Fig. 1, it will be seen that we have illustrated the common form of bunker 60 wherein a drain pan 11 is provided and the usual grab irons 12 are mounted on the outside of the car and the hatches 14 and foot board 15 on the top thereof. The arrangement of the contrivance may be understood by referring to Fig. 1, wherein it is shown positioned in the bunker. All bunkers on the common refrigerator cars as is well known, are at the end of the car, one at each end.

This space varies an inch or two on the different types, but there is no material difference in any of them and the contrivance may be made of a standard size for all bunkers. This bunker space extends from the roof of the car to the grating, which grating rests on approximately six by six sills, which in turn rest on another set of sills, making the top of the grating about eighteen inches from the bottom of the car, 80 outside measurements. The depth of the bunker is about six feet six inches at the center. The width is about thirty-two inches. The length is about eight feet two inches. The wood gratings now in use are 85 usually made of oak lumber turned up sideways and spaced about two inches apart to prevent the pilfering of the car. These gratings can be easily cut out or sprung, whereas with our contrivance therein, this 90 will be made practically impossible.

With our grating and spray in place, either on top of the old grating or with the old grating removed, the car can be iced and shipped, then when it is to be returned instead of hauling the ice across the continent, a connection can be made to the pipe 9 as explained, and the water turned on so that the ice can be quickly melted out.

It is thought that the construction, operation, and utility of this contrivance will now be clearly understood by those skilled in this art without a more detailed description thereof. The present embodiment of the invention has been disclosed in detail 105 merely by way of example since in actual practice it attains the features of advantage enumerated as desirable in the statement of the invention and in the above description. It will be apparent that numerous changes 110

in the details of construction, and in the combination and arrangement of parts as well as in the proportions and sizes thereof may be resorted to without departing from the spirit or scope of the invention as herein-after claimed, or sacrificing any of its advantages.

Having thus described our invention, what we claim as new is:—

70. In combination with the bunker of a re-

frigerator car, a combined grating and spray contrivance in the bottom thereof formed with a rectangular tubular frame having a plurality of tubes across the frame, and a pipe rising from the corner thereof, said 15 tubes and frames being perforated.

In testimony whereof we affix our signatures.

LAWRENCE CRUNCLETON.
